TYPE RACK

Joshua Bailey, West Bromwich, England

Application February 14, 1935, Serial No. 6,476
In Great Britain February 22, 1934

9 Claims. (Cl. 276—45)

The present invention relates to type racks of the kind including carriers of channel or slotted tubular form and the object of the invention is to provide a new or improved type rack, wherein 5 the said tubes or carriers full of type may be mounted, the rack being constructed so that the type can be withdrawn one by one in a convenient manner for use, and the empty carriers removed and replaced by loaded carriers as required.

Referring to the drawings:—

Figure 1 is a front elevation showing a type rack or support according to the present invention.

15 Figure 2 is a sectional plan view of same.

Figure 3 shows same in sectional end elevation.

Figure 4 is a perspective view of one end of one of the type carriers illustrated in Figures 1 to 3.

20 Figure 5 is a perspective view of the lower bar of the support illustrated in Figures 1 to 3.

Figure 6 illustrates the arrangement of a plurality of supports in a cabinet or framework.

In the construction illustrated in the accompanying drawings the apparatus comprises a cabinet or structure 8 in which a number of supports are arranged in inclined but spaced parallel planes, as shown in Figure 6, the forward edges of all the supports being disposed in a 25 substantially vertical plane adjacent the front of the cabinet or structure so that ready access can be obtained to all the supports.

Each support comprises an open frame 9, each side or arm of which is of angle section, the top 35 of the frame being disposed in a common plane and being adapted to support type carriers 10 for receiving the type.

Each carrier is in the form of a slotted tube or channel and is pressed from a blank or strip 40 of metal to the section shown in Figures 2 and 4, the edges of the blank or strip being bent to project inwardly across the channel to form overhanging edges for engaging in the reduced waist portions 11 of the type 12, as shown in Figure 2.

45 The tail pieces of the type are received within the tubes or channels, whilst the type surface projects from the carrier tubes.

The rear surface or side 13 of each carrier is flattened to seat firmly upon the support and in 50 this flattened side and at each end of the carrier is provided a longitudinal slot 14, shown clearly in Figure 4.

Along the lower side of the frame 9 is secured, by means of screws 15, a supporting bar 16 provided along its upper edge with a number of

projecting tongues 17 which extend transversely of the bar in spaced but parallel relationship and at positions corresponding with the desired positions of the carrier tubes upon the support.

Each tongue 17 is of reduced width at its upper end and at its lower end is under cut or of dovetail section and each carrier tube is mounted in position by engaging the slot 14 at the lower end of the carrier with one of the tongues 17. The reduced upper end of the tongue permits the 10 carrier to be engaged readily therewith, but when the edges of the slot 14 engage with the dovetailed lower portion of the tongue the tube is retained in position upon the support.

Below the tongues 17 the bar 16 is recessed at 15 18 and a rail 19 is secured in this recess by means of rivets 20.

The rail 19 is formed with a plurality of delivery chutes 21 which extend transversely across the rail in parallel relationship and at spacing 20 corresponding with the spacing of the tongues 17, such that when the rail 19 is secured to the bar 16 each chute 21 is aligned with one of the tongues 17.

At the lower edge of the bar 16 and projecting 25 from the latter at the lower side of the recess 18 are a number of integral stop projections 23 also located in alignment with the projections 17, so that when the rail 19 is mounted in position each of the projections 23 is located directly beneath 30 one of the chutes 21 to form a retaining stop.

The rail 19 is cut away along its lower edge to provide a gap between the lower end of the chutes and the upper surface of the stop projections 23 and this cut away portion is stepped 35 or of varying width, as shown in Figure 1, so that the gaps between the various chutes and their corresponding stops are of different widths.

Each chute 21 is of enlarged or diverging form at its upper or inlet end 24 to facilitate the passage of type from the carrier tubes into the delivery chutes when the rack is assembled as shown in Figures 1 and 3.

Along the upper side of the frame 9 is secured a further bar 25 provided with integral projections 26 at spacings corresponding with the spacings of the tongues 17, the arrangement being that when the lower end of a carrier tube has been engaged with one of the tongues 17, the slot at the upper end of the tube can be engaged over 50 the corresponding projections 26 so that the tube is located at both ends relative to the support.

The projections 26 are not of dovetail or under cut section so that the carrier tubes can be pressed into engagement with the projections 26 55

after they have been completely engaged with the tongues 17, but by making the projections 26 of width slightly greater than the normal width of the slots 14 at the upper end of the carrier tubes, the latter can be sprung into engagement with the projections 26 and retained by the resilience or spring in the end of the tube itself.

If desired, however, the projections 26 may be slightly under cut to facilitate retention of the carrier tubes.

Each carrier tube is loaded with type of a particular kind and is then mounted upon the support by first engaging the slot at the lower end of the tube with the corresponding tongue 17, and when the carrier is in position with its lower end adjacent the upper end of the delivery chute the slot 14 at the upper end of the tube is engaged with the corresponding projection 26 by pressing the tube over the projection which 20 springs between the edges of the slot.

The type in the carrier slide down by gravity into the delivery chute which forms a continuation of the carrier and receives the tail pieces of the type, whilst the overhanging edges of the 25 chute engage in the reduced waist of the type.

The lowest type in the delivery chute drops out of the lower end thereof and comes to rest upon the corresponding stop 23 and the carrier tube for the particular type is located upon the support in such a position that the gap between the lower end of the corresponding delivery chute and the upper surface of the stop is of width equal to or greater than the width of face of the particular type, but is less than twice the width of the 35 type face.

Thus, only one tape at a time can move out of the lower end of the chute and until the lowest type is removed the remaining type are retained either in the carrier or in the delivery chute.

In connection with printing machines of the kind known as office appliances, it is usual to employ type which are all of the same width, but the present invention is primarily intended for type for use in commercial printing machines, 45 wherein the width of the type varies considerably.

Thus, it is necessary to arrange the carriers at suitable positions upon the support so that the gap at the lower end of the delivery chute is of sufficient width to accommodate one type, but is 50 insufficient to enable the two lowest type in the delivery chute to be free. It is not essential that the gap should be of width exactly corresponding with the width of the particular type as long as only the lowest type is entirely freed from the 55 delivery chute and the next succeeding type is engaged to some extent in the end of the delivery chute.

It is thus possible to arrange the steps in this gap in a number of average widths so that types 60 of widely differing widths can be accommodated in one or other of the chutes.

The type can be removed from the support by sliding the lowest type of the desired kind from the bottom of the corresponding column and 65 when this lowest type has been removed the next lowest drops into the delivery position and any number of type can be fed in succession from the delivery chute, although it is impossible to obtain delivery of two type simultaneously from 70 the same chute or carrier.

When the supply of type from any particular carrier tube is exhausted, the empty tube can be removed and a number of this particular type are 75 available in the corresponding delivery chute

pending the replacement of the empty carrier by a full carrier of type.

Any carrier can quickly be removed from the support and a loaded carrier can be mounted in the correct position with the minimum possible delay, but if desired, manually operable means may be provided for retaining the upper ends of the carrier tubes in position, such for example, as small spring pressed bolts mounted upon the upper bar 25 or the upper side of the frame 2. 10

The present invention is primarily intended for use with dwarf type, i. e. type having very short stems.

What I claim then is:—

1. A type rack including a supporting frame, a 15 supporting bar along the lower side of said frame, a plurality of delivery chutes arranged in spaced parallel relationship along said bar, each of said chutes being open at each end, a plurality of dovetailed projections on said bar, each of said 20 projections being disposed in alignment with the open upper end of one of said delivery chutes, a plurality of detachable type carriers, each of said carriers being of slotted tubular form and 25 having at its lower end a slot the edges of said slot being engageable with the dovetailed edges of one of said projections to locate said carrier in alignment with a delivery chute, a plurality of rigid stop projections on said bar disposed beneath the lower end of each of said delivery 30 chutes to prevent type leaving said chute inadvertently, said bar having a gap between the lower end of each delivery chute and its associated stop projections enabling type to be removed one at a time through said gap and the 35 gaps for different chutes being of different depths to permit the type of different widths being accommodated on the rack.

2. A type rack including a supporting frame, a supporting bar along the lower side of said 40 frame, a plurality of delivery chutes arranged in spaced parallel relationship along said bar, each of said chutes being open at each end, a plurality of locating projections on said bar, each of said 45 projections being disposed in alignment with the open upper end of one of said delivery chutes, a plurality of detachable type carriers, each of said carriers being of slotted tubular form and having at its lower end a slot engageable with one of said 50 projections to locate said carrier in alignment with a delivery chute, a plurality of rigid stop projections integral with said bar, each of said stop projections being disposed beneath the lower end of one of said delivery chutes, said bar 55 having a gap between the lower end of each delivery chute and its associated stop projections to allow the lowest type to leave the end of said chute for removal through gap, but with the next lowest type retained by edges of said chute until the said lowest type has been removed, and the gaps for different chutes being of different depths to permit the type of different widths being accommodated on the rack.

3. A type rack including a supporting frame, a supporting bar along the lower side of said 65 frame, a plurality of delivery chutes extending transversely across said bar in spaced parallel relationship, each of said chutes being open at each end, a plurality of locating projections on said bar, each of said projections comprising a tongue of dovetail section extending transversely across said bar immediately above and in alignment with the open upper end of one of said delivery chutes, a plurality of detachable type car- 70 75

- riers, each of said carriers being of slotted tubular form and having at its lower end a slot engageable with one of said projections to locate said carrier in alignment with a delivery chute, 5 a further supporting bar along the upper side of said frame, a plurality of locating projections on said bar corresponding with the projections on said lower supporting bar, each of said type carriers having an opening engageable with one of the 10 projections on said further supporting bar, a plurality of rigid stop projections at the lower edge of said bar, each of said stop projections being disposed beneath the lower end of one of said delivery chutes, said bar having a gap between the lower end of each delivery chute and its associated stop projection to allow the lowest type to leave the end of said chute for removal through the gap between the stop and the lower end of the delivery chute, but with the next lowest 15 type retained by said chute until the said lowest type has been removed, and the gaps for different chutes being of different depths to permit the type of different widths being accommodated on the rack.
- 15 4. A type rack including a supporting frame, a supporting bar along the lower side of said frame said bar being recessed longitudinally, a rail mounted in said recess, a plurality of delivery chutes arranged in spaced parallel relationship along said rail, each of said chutes being open at each end, a plurality of locating projections on said bar, each of said projections being disposed in alignment with the open upper end of one of said delivery chutes, a plurality of detachable type carriers, each of said carriers being of slotted tubular form and having at its lower end an opening engageable with one of said projections to locate said carrier in alignment with a delivery chute, on said bar for each of said chutes, each 20 of said stops being disposed beneath the lower end of one of said delivery chutes, but being spaced therefrom sufficiently to allow the lowest type to leave the end of said chute for removal through the gap between the stop and the lower end of the delivery chute, but with the next lowest type retained by said chute until the said lowest type has been removed and the spacing of the corresponding stop being unequal for the several chutes to accommodate type of different 25 widths.
- 25 5. A type rack including a supporting frame, a supporting bar along the lower side of said frame, said bar being recessed longitudinally, a rail mounted in said recess, a plurality of delivery chutes arranged in spaced parallel relationship along said rail, a plurality of locating projections on said bar, each of said projections being disposed in alignment with the open upper end of one of said delivery chutes, a plurality of detachable type carriers, each of said carriers being formed from a sheet metal blank bent into channel form with overhanging edges, each type carrier having at its lower end an opening engageable with one of said projections to locate said carrier in alignment with a delivery chute, a plurality of stops on said bar below said recess, each of said stops being disposed beneath the lower end of one of said delivery chutes, said bar having a gap between the lower end of each delivery chute and its associated stop projection to allow the lowest type to leave the end of said chute for removal through said gap but with the next lowest type retained by said chute until the said lowest type has been removed, and the gaps for different chutes being of different depths to permit the type of different widths being accommodated on the rack.
- 30 6. A type rack including a casing, a supporting frame mounted in an inclined position in said casing, said frame being of open rectangular form, a supporting bar along the lower side of said frame, said bar being recessed longitudinally, a rail mounted in said recess, a plurality of delivery chutes arranged in spaced parallel relationship along said rail, a further supporting bar 10 along the upper side of said frame, locating projections at corresponding positions on said supporting bars, a plurality of detachable type carriers, each of said carriers being of slotted tubular form and having openings for engaging corresponding projections on said upper and said lower supporting bar to locate said carrier in alignment with a delivery chute, a plurality of integral rigid stops on said bar below said recess, each of said stops being disposed beneath the lower end of one of said delivery chutes, said bar having a gap between the lower end of each delivery chute and its associated stop projection to allow the lowest type to leave the end of said chute for removal through said gap, but with the next lowest type retained by said chute until the said lowest type has been removed, and the gaps for different chutes being of different depths to permit the type of different widths being accommodated on the rack.
- 35 7. A type rack including a casing, a plurality of supporting frames mounted one above the other in said casing and in spaced parallel planes inclined to the horizontal, each of said frames having a lower supporting bar, a plurality of delivery chutes extending transversely of said bar, an upper supporting bar, locating projections at corresponding positions on said supporting bars, a plurality of detachable type carriers, each of said carriers being of slotted tubular form 40 and having openings for engaging corresponding projections on said upper and said lower supporting bar to locate said carrier in alignment with a delivery chute, a plurality of rigid stops on said bar, each of said stops being disposed beneath the lower end of one of said delivery chutes, said bar having a gap between the lower end of each delivery chute and its associated stop projection to allow the lowest type to leave the end of said chute for removal through said gap, but with the next lowest type retained by said chute until the said lowest type has been removed and the spacing of the corresponding stop being unequal for the several chutes to accommodate type of different 45 widths being accommodated on the rack.
- 40 8. A type rack including a casing, a plurality of supporting frames mounted one above the other in said casing and in spaced parallel planes inclined to the horizontal, each of said frames having a lower supporting bar, a plurality of delivery chutes extending transversely across said bar in spaced parallel relationship, each of said chutes being open at each end, and the open upper end being of diverging form to facilitate the passage of type into said chute, an upper 50 supporting bar, locating projections at corresponding positions on said supporting bars, a plurality of detachable type carriers, each of said carriers being of slotted tubular form and having openings for engaging corresponding projections on said upper and said lower supporting bar to locate said carrier in alignment with a delivery chute, a plurality of rigid stops integral with said lower supporting bar, each of said stops being disposed beneath the lower end of one of said 55 chutes.
- 45 9. A type rack including a casing, a plurality of supporting frames mounted one above the other in said casing and in spaced parallel planes inclined to the horizontal, each of said frames having a lower supporting bar, a plurality of delivery chutes extending transversely across said bar in spaced parallel relationship, each of said chutes being open at each end, and the open upper end being of diverging form to facilitate the passage of type into said chute, an upper 60 supporting bar, locating projections at corresponding positions on said supporting bars, a plurality of detachable type carriers, each of said carriers being of slotted tubular form and having openings for engaging corresponding projections on said upper and said lower supporting bar to locate said carrier in alignment with a delivery chute, a plurality of rigid stops integral with said lower supporting bar, each of said stops being disposed beneath the lower end of one of said 65 chutes.
- 50 10. A type rack including a casing, a plurality of supporting frames mounted one above the other in said casing and in spaced parallel planes inclined to the horizontal, each of said frames having a lower supporting bar, a plurality of delivery chutes extending transversely across said bar in spaced parallel relationship, each of said chutes being open at each end, and the open upper end being of diverging form to facilitate the passage of type into said chute, an upper 65 supporting bar, locating projections at corresponding positions on said supporting bars, a plurality of detachable type carriers, each of said carriers being of slotted tubular form and having openings for engaging corresponding projections on said upper and said lower supporting bar to locate said carrier in alignment with a delivery chute, a plurality of rigid stops integral with said lower supporting bar, each of said stops being disposed beneath the lower end of one of said 70 chutes.
- 55 11. A type rack including a casing, a plurality of supporting frames mounted one above the other in said casing and in spaced parallel planes inclined to the horizontal, each of said frames having a lower supporting bar, a plurality of delivery chutes extending transversely across said bar in spaced parallel relationship, each of said chutes being open at each end, and the open upper end being of diverging form to facilitate the passage of type into said chute, an upper 75 supporting bar, locating projections at corresponding positions on said supporting bars, a plurality of detachable type carriers, each of said carriers being of slotted tubular form and having openings for engaging corresponding projections on said upper and said lower supporting bar to locate said carrier in alignment with a delivery chute, a plurality of rigid stops integral with said lower supporting bar, each of said stops being disposed beneath the lower end of one of said chutes.

5 delivery chutes to prevent type leaving said chute inadvertently, said bar having a gap between the lower end of each delivery chute and its associated stop projection enabling type to be removed one at a time through said gap and the gaps for different chutes being of different depths to permit the type of different widths being accommodated on the rack.

9. A type rack including a casing, a plurality 10 of supporting frames mounted one above the other in said casing and in spaced parallel planes inclined to the horizontal, each of said frames having a lower supporting bar, said bar being recessed longitudinally, a rail mounted in said 15 recess, a plurality of delivery chutes extending transversely across said rail in spaced parallel relationship, each of said chutes being open at each end, and the open upper end being of diverging form to facilitate the passage of type 20 into said chute, an upper supporting bar, locating projections at corresponding positions on said

supporting bars, a plurality of detachable type carriers, each of said carriers being of slotted tubular form and having openings for engaging corresponding projections on said upper and said lower supporting bar to locate said carrier in alignment with a delivery chute, a plurality of rigid stop projections on said lower supporting bar below said recess, each of said stop projections being disposed beneath the lower end of one of said delivery chutes, said bar having a gap 10 between the lower end of each delivery chute and its associated stop projection to allow the lowest type to leave the end of said chute for removal through said gap, but with the next lowest type retained by said chute until the said lowest type 15 has been removed, and the gaps for different chutes being of different depths to permit the type of different widths being accommodated on the rack.

JOSHUA BAILEY. 20
